WALL CLOSET

Filed April 20, 1923.

2 Sheets-Sheet 2

UNITED STATES PATENT OFFICE.

CHARLES R. HAMLIN, OF CHICAGO, ILLINOIS.

WALL CLOSET.

Application filed April 20, 1923. Serial No. 633,490.

To all whom it may concern:

Be it known that I, CHARLES R. HAMLIN, a citizen of the United States, residing at Chicago, in the county of Cook and State of Illinois, have invented certain new and useful Improvements in Wall Closets, of which the following is a specification.

My present invention has for its object the provision of a simple inexpensive portable device which may be easily secured to a fixed support and by which a number of articles of clothing may be firmly supported and protected against dust. The invention is illustrated in the accompanying drawings and will be hereinafter fully set forth.

In the drawings:

Figure 1 is a perspective view of one embodiment of the invention arranged for use;

Fig. 2 is a side elevation of the device, the supporting arm being shown lowered in Fig. 1 and raised in Fig. 2;

Fig. 3 is a detail perspective view showing another embodiment of the invention, and

Fig. 4 is a side elevation showing a form of supporting arm different from that shown in Figs. 1 and 2.

In carrying out my invention, I employ a base 1 which may conveniently be a block of hard wood having openings formed therethrough between its ends whereby fastening screws 2 or similar devices may be inserted into a wall or other fixed support. To this base at the lower end thereof, I secure a socket or supporting bracket 3 which will preferably be of pressed steel and presents side leaves adapted to bear flat against the front face of the base and be rigidly secured thereto and a central supporting portion comprising spaced lugs 4 between which one end of the supporting arm 5 is pivoted. In Figs. 1 and 2, the supporting arm is shown as consisting of a single piece of stout wire bent to present the shank or body member 12 and suspending lugs 13 projecting therefrom. An eye 14 is formed at the lower end of the shank to permit the same to be pivotally secured between the lugs 4 and the tongues 9 will be located close enough together to firmly engage the shank and support it in upright position. The upper ex-

tremity of the shank is projected slightly forward, as shown at 15, whereby it forms a convenient handle or gripping portion to facilitate the lowering of the arm when the removal or suspension of garments is to be effected. Each lug 13 is formed at its extremity with an eye 16 in which garment hangers 8 may be engaged, and these arms or hooks are so disposed that in the upright position they will be inclined upwardly from the shank and the base 1 and may, therefore, be used to support hats or similar articles. When garments are to be removed, the supporting arm 5 may be swung downwardly, as shown in Fig. 1, so as to bring the garment hangers within convenient reach and when the removal of garments or the suspending of the same is not desired, the arm is swung upwardly against the base 70 to the position shown in Fig. 2 and will be supported in said upright position by a retainer consisting of resilient tongues 9 bent from an attaching shank 10 which is rigidly secured to the base, as clearly shown, and the 75 tongues, as shown clearly in Fig. 1, have divergent extremities so that the arm may readily ride into and out of engagement therewith.

In Fig. 4, I have shown the arm formed of 80 cast steel having spaced lugs 6 on its front side provided with openings 7 therethrough whereby garment hangers 8 may be engaged in the said lugs and suspended therefrom. The arm is provided upon its side edges 85 with longitudinal ribs or flanges 11 so that it may be readily and firmly engaged by the retaining tongues 9.

Above the clip or retainer 9, I secure to the base a loop or suspending bracket 17 90 which extends across the front of the base in spaced relation thereto and is adapted to carry a curtain-supporting member 18. In Figs. 1 and 2 this supporting loop is shown as constructed of wire having eyes 19 at its 95 ends through which fastening devices are inserted into the edges of the base and having its central portion disposed across the front of the base in position to admit the hooks 20 of the curtain-carrying device 18. 100 The said curtain-carrying device is shown as consisting of a stout wire or light rod

2
bent upon itself to provide upper and lower parallel branches connected integrally at one end, as shown at 21, and having a retaining hook 22 at the opposite end of one branch 5 or member adapted to receive the pointed end 23 of the other branch or member. The upper branch is bent laterally to form the hooks 20 and the extremities of said hooks are connected by a bridge 24, as clearly shown in Fig. 1. A curtain 25 of any suitable textile material is suspended from the carrying member 18 and is secured thereon by having the pointed end of the lower branch of said member threaded through the upper edge or hem of the fabric. As shown most clearly at 26 in Fig. 1, the curtain is formed in two sections which have their inner edges overlapping so that garments suspended on the main supporting arm will be 10 completely covered by the curtain and thereby protected from dust or other damaging elements. In applying the curtain-carrying member to the base, the ends of the hooks 20 and the bridge connecting the same are disposed against the base below the loop 17 and the device is then slid upwardly on the base so that the said bridge and the ends of the hooks will pass between the loop and the base, after which the curtain-carrying member 15 20 25 30 35 is swung pivotally about the loop so as to assume the position shown in Figs. 1 and 2, in which position it will be firmly supported by the loop.

At the upper extremity of the base, I secure a retaining loop 27 in which is engaged the depending base or rest portion 28 of a hat-supporting member or rack 29, the said hat-supporting member consisting of a ring formed integral with the rest 28 and projecting forwardly from the base, as clearly shown. A hat to be supported is engaged with its crown downward through the ring 29, as shown in Fig. 2, and other hats may be nested within the first hat in an obvious manner so that several hats may be supported by the one ring.

In Fig. 3, I have shown a curtain-carrying member slightly different from the curtain-carrying member shown in Figs. 1 and 50 55 60 65 70 75 80 85 90 95 100 105 110 115 120 125 130 135 140 145 150 155 said bracket, one of the strands being formed, at intervals in its length, to provide two-strand hanger-supporting arms having terminal eyes to accommodate the hooks of 5 garment hangers, the arms extending from the shank at an acute angle thereto in the direction of the free end of the shank, the said member being movable about its pivot to assume a substantially horizontal position 10 and an upright position in front of the base,

and means upon the base for maintaining the member in the last mentioned position, the free end portion of the member being deflected to provide a handle portion extending forwardly at an angle from the base 15 in the said last mentioned position of the member.

In testimony whereof I affix my signature.

CHARLES R. HAMLIN. [L.S.]
